Primary Examiner — Mary Ann Calabrese*Assistant Examiner* — Katelin G Kloberg(74) *Attorney, Agent, or Firm* — Crawford Intellectual Property Law LLC; Brie A. Crawford(57) **CLAIM**

The ornamental design for a table, as shown and described.

DESCRIPTION

FIG. 1 depicts a top, front perspective view of a table showing my new design;

FIG. 2 depicts a front elevational view thereof;

FIG. 3 depicts a rear elevational view thereof;

FIG. 4 depicts a top plan view thereof;

FIG. 5 depicts a bottom plan view thereof;

FIG. 6 depicts a left elevational view thereof; and,

FIG. 7 depicts a right elevational view thereof.

1 Claim, 6 Drawing Sheets
